UNITED STATES PATENT OFFICE.

WILLIAM THOMAS STRATTON, OF BILLINGS, MONTANA.

PUMP ATTACHMENT FOR AUTOMOBILES.

1,350,122.

Specification of Letters Patent. Patented Aug. 17, 1920.

Application filed February 19, 1920. Serial No. 359,764.

To all whom it may concern:

Be it known that I, WILLIAM THOMAS STRATTON, a citizen of the United States of America, residing at Billings, in the county 5 of Yellowstone and State of Montana, have invented certain new and useful Improvements in Pump Attachments for Automobiles, of which the following is a specification.

10 This invention relates to a pump attachment for automobiles and it has for its object to provide a construction which may be easily and quickly included in the water circulating systems of automobiles which ordinarily employ the thermosiphon system, to thereby increase the circulation in such systems. The structure shown in the accompanying drawing is particularly intended for application to the well-known Ford automobile.

Further objects and advantages of the invention will be set forth in the detailed description which now follows.

In the accompanying drawing Figure 1 is 25 a side elevation of a Ford engine having the invention applied thereto, Fig. 2 is a transverse vertical section with certain of the parts omitted; Fig. 3 is a detailed view of the bracket hereinafter described, and Fig. 4 is a detail sectional view through the bearing.

Like numerals designate corresponding parts throughout the several figures of the drawing.

5 Referring to the drawing, 5 designates the well known Ford engine and 6 designates a pump comprising an outlet 7 that is adapted to be bolted directly to the water jacket of the engine at the place where the upper side hose connection is ordinarily attached. The inlet 8 of the pump is adapted to have connection with a special pipe connection 9 that is so shaped as to extend substantially horizontally for a distance and then at an angle as indicated at 9^a, this last angle corresponding to the angle at which the lower hose or pipe connection of the Ford circulating system usually lies.

The shaft 10 of the pump carries a pulley 11 adapted to be driven from the Ford motor, preferably by a belt which also

acts as the fan belt 11^a. The outer end of this shaft is mounted in a bearing of particularly novel construction, by means of which bearing the parts may be quickly put 55 in place without danger of binding of the shaft of the pump. This bearing comprises a bracket 12 having slotted openings 13, which receive bolts 14, that take into the cover of the time gear case. This construction provides for bodily vertical adjustment of the bracket. The bracket further comprises a horizontally-disposed overhanging plate 15 which has elongated slots 16 formed therein for the reception of bolts 16^a which 60 engage a bearing block 17, and it is in this bearing block that the outer end of the shaft 10 is mounted to turn. The provision of the elongated openings 16 permits of a lateral adjustment of the bearing block 17, and this 65 coupled with the vertical adjustment already described renders it possible to quickly adjust the bearing to support the shaft without binding. It will be noted that the bearing block comprises the body portion 17 and 70 face plates 18 and 19, the latter being provided with the openings through which the shaft passes and in which the shaft turns.

It is to be understood that the invention is not limited to the precise construction set 75 forth but that it includes within its purview whatever changes fairly come within the terms or the spirit of the appended claims.

Having described my invention what I claim is:

1. A device of the character described comprising a bearing and a bracket for supporting the same, said bracket consisting of an inclined arm having a substantially horizontal plate at one end thereof, the plane of 80 which is at right angles to the plane of the inclined arm and a web at the opposite end of said arm which lies in the plane of said arm and extends in opposite directions therefrom, said web and said plate each having 85 elongated slots formed therein, a bearing block and fastenings for the bearing block adjustable in the slots of the plate.

2. A device of the character described comprising a pump, means for attaching the 90 same to the side of a Ford water jacket to have connection therewith, a shaft extending

in substantial parallelism with the side of the engine for driving said pump, a pulley on said shaft, a bracket support from the engine and capable of vertical adjustment with respect thereto, and a bearing horizontally adjustable upon the bracket within which said shaft is mounted.

In testimony whereof I affix my signature in the presence of two witnesses.

WILLIAM THOMAS STRATTON.
